SMOKE WASHING APPARATUS

Filed Aug. 9, 1929

REISSUED

UNITED STATES PATENT OFFICE

CHARLES M. GERHOLD, OF NEW YORK, N. Y.

SMOKE-WASHING APPARATUS

Application filed August 9, 1929. Serial No. 384,730.

The invention relates to improvements in smoke washing apparatus applicable to any of the known types of chimney structure and particularly serviceable as a means of entirely eliminating soot, ashes, débris, and other objectional particles from the smoke emanating from chimney stacks and other exhaust ducts of a like nature.

The invention comprises supporting means at and upon the exhaust end of the chimney or other like structure and of the attachment thereto of a trough or water reservoir having mounted thereon means supporting an accumulator hood or dome carrying a suitable baffle means arranged to pocket an amount of the gases emanating from the chimney to form a cushion or buffet body for the smoke, gases, etc., passing therefrom, and upon which cushion said smoke, gases, etc. impinge and are deflected through a water curtain or screen formed by a water supply disposed in said dome, thus washing and clarifying said smoke and gases and precipitating all deleterious substances therefrom, to the trough or reclamation means whence it is returned through suitable drainage means to any point of deposit, permitting only the substantially clarified and purified vapors to emit from the stack.

The essential object of the invention resides in the super-imposing upon the emitting end of a chimney or stack of a specially formed deflector hood provided with a baffle wall arranged to accumulate an amount of gas to act as a buffer cushion against which the smoke contacts to form a vacuum head and deflect the smoke and gases therefrom through the water curtain, thoroughly washing said smoke and precipitating all solids to the reclamation trough whence same may be carried off through suitable gravity exhaust means, the action of the smoke and gasses passing from such chimney or stack functioning as a draft or vacuum head for the generator unit.

In the following there is described one embodiment of the invention, the features thereof being more clearly defined hereinafter in the claims.

In the drawings, Fig. 1 is a vertical sec-

tional view of the smoke washing apparatus as applied to the emitting end of any of the known types of chimney or stack ends; Fig. 2 is a plan cross section on the line 2—2 of Fig. 1 of the accumulator trough showing in cross section the deflector head and the water ejector means for forming the clarifying water curtain; Fig. 3 is a cross sectional view of the water head showing the position thereon of a water ejector nozzle or nipple; and Fig. 4 is an under elevation of the water head showing the position therein of the ejector nozzles and of the specific formation of the water ducts or apertures for casting a fan like stream to form the water curtain or washing means.

In the following similar numerals of references indicate similar parts throughout the drawings, forming part hereof.

In the drawings 1 designates a chimney or stack structure having disposed upon its exhaust or emitting end a secondary chimney structure comprising a supporting collar or sleeve 2, carrying an annular rib 3 to which an accumulator or reception trough 4 is attached, said trough 4 receiving part of its support upon the rim or top of said exhaust structure 1.

Trough 4 is of partly frusta-conical form inverted and provided at its lower portions with a horizontal section 5 to form between the conical wall 6 and the outer surface 7 of supporting sleeve 2, a water or reclamation chamber 8, and at the top of said conical wall 6 a circular sleeve 9 forming the exhaust or emitting end of the stack 1. Wall 6 of trough 4 has mounted thereon a series of supporting brackets 10 having disposed therein bolts 11 which have mounted thereon and adjustable vertically with relation thereto a cone-like accumulator hood or dome 12. The peripheral edge of dome 12 has mounted thereon clips 13 engaging said bolts 11 the same being adjustably secured thereon by means of nuts 14.

Said dome or hood 12 has mounted on its under side and within the conical confines thereof a baffle sleeve or annular plate 15 arranged to form the means of accumulating of gas from the stack to form the smoke cushion or buffer deflector means. A water head, 16,

is mounted within said dome on the outside of said baffle sleeve 15 immediately above the trough section 5 of the accumulator and consists of a coiled pipe 17 having mounted 5 therein a plurality of nipples 18 each provided with apertures 19 merging with elliptical vents 20 for spray forming means arranged to deflect a water spray of fan like formation 21 between each nipple to thus 10 form a complete circular or annular water curtain around the main vent or passageway 22 between the exhaust end of stack 1 and atmosphere, providing therefor a washing means through which every particular of 15 smoke, gas, heavier than air particles etc. from stack 1 must pass to be completely clarified.

Within dome 12 and above baffle sleeve 15 a gas chamber 23 is formed to receive the 20 gases, etc., from stack 1 to act as the draft or semi-vacuum means for assisting the draft of said stack 1.

Water head 16 is connected with a fresh water supply pipe 24 connected with any 25 source of water supply, and section 5 of accumulator 4 has mounted therein an exhaust or waste pipe 25 arranged to carry off by gravity the sludge and other substances washed from the smoke, gases, etc., emitted 30 by the chimney or stack.

The invention may be varied in structural form in many ways without departing from the spirit of the same as is shown, described and claimed herein.

35 What is claimed and desired to secure by Letters Patent of the United States is:

1. A device of the character described comprising an auxiliary supporting means disposed upon a chimney outlet, a reservoir 40 mounted thereon, a receiving chamber formed in said reservoir between the outer wall of said auxiliary supporting means and the inner wall of said reservoir, supporting means carried by said reservoir, an accumulator hood 45 adjustably disposed upon the supporting means in said reservoir, an annular vertically disposed baffle means mounted in said hood arranged to form within the conical dome thereof a gas cushioning chamber, a water 50 head mounted in said hood on the outer wall of said baffle means provided with a plurality of nipples having apertures adapted to project a fan like spray across the vent between said reservoir and hood to form the water 55 curtain for clarifying the smoke and gases emitted by said chimney.

2. A device of the character described comprising a secondary chimney structure mounted on the exhaust end of a smoke stack; a 60 partly conically shaped reservoir mounted thereon, a water and sludge receiving chamber formed in said reservoir, supporting brackets carried by said reservoir and disposed on the conical walls of said reservoir, 65 supporting bolts mounted in said brackets,

an accumulator hood mounted on said bolts and adjustable vertically with relation thereto, and annular baffle means mounted in said hood and depending therein to form within said hood a gas cushioning chamber, a water head mounted in said hood and disposed around the outside of said baffle means provided with a plurality of spray nipples arranged to project an uninterrupted water curtain across the vent between said reservoir and the peripheral edge of said hood, a water supply pipe connecting said water head with a water supply source, and a pipe connection mounted in the chamber of said reservoir arranged to carry off the sludge precipitated therein from the washing of the smoke from said stack.

3. A device of the character described comprising a supporting collar mounted in the emitting end of a chimney, an inverted conically shaped reservoir mounted on said collar, a sludge receiving chamber in said reservoir, supporting brackets mounted on the inside conically shaped walls of said reservoir, a series of supporting bolts mounted in said brackets, an accumulator hood mounted on said bolts and adjustable vertically to and away from the exhaust end of said collar to vary the vent between said reservoir and hood, an annular baffle sleeve mounted in the dome of said hood, a water head mounted in said hood and disposed around the outer wall of said baffle sleeve adapted to project a water curtain across the vent between said reservoir and hood to the chamber in said reservoir, a plurality of nipples mounted in said water head provided with emitting apertures arranged to project said water curtain in an annular uninterrupted column circumferentially around the exhaust end of said chimney to clarify the smoke passing through said vent, a pipe connection forming means for supplying water to said water head, and an exhaust pipe connection mounted in said reservoir in the receiving chamber thereof arranged to carry off the sludge precipitated therein.

In testimony whereof I affix my signature.
CHARLES M. GERHOLD.
